Primary Examiner — Carol P Rademaker*(74) Attorney, Agent, or Firm* — Bakers Botts L.L.P.(57) **CLAIM**

The ornamental design for a plastic container, as shown and described.

DESCRIPTION

FIG. 1 is a top, front, left side perspective view showing our design for a plastic container;

FIG. 2 is a bottom, rear, left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawing views are included for the purpose of illustrating portions of the plastic container that form no part of the claimed design.

1 Claim, 7 Drawing Sheets(56)
